PAPER FEEDING AND CUTTING APPARATUS

Abe H. Markowitz, Los Angeles, Calif.

Application October 8, 1934, Serial No. 747,352

27 Claims. (Cl. 164—68)

This invention relates to improvements in apparatus for feeding paper from a roll in a continuous strip, cutting it into various standard lengths and feeding the severed sheets to a printing machine operable in synchronism therewith.

The object of my invention is to provide apparatus of practicable and relatively simple construction for supplying paper in a continuous web to any of the various types of portable printing machines using stencils, type or other form of ink-impression or transfer, and to sever the paper prior or simultaneously to delivery to the printing machine into any of the usual lengths.

Other objects and advantages residing in my invention, and objects relating to the details of construction and arrangements of parts thereof, will be readily apparent and fully set forth in the detailed description to follow.

The accompanying drawings illustrate by way of example an operative embodiment of my invention, in which:

Figure 1 is a view in side elevation of an embodiment of my invention shown in relation to a printing machine.

Fig. 2 is a view in top plan of the same on a larger scale.

Fig. 3 is a view partly in longitudinal section and partly in side elevation.

Fig. 4 is a view in side elevation of that portion of the invention relating to the power transmission devices.

Fig. 5 is a detail view partly broken away and in cross-section of the knife-head element of the invention and associated parts.

Referring to said views, the reference numeral 1 indicates the horizontal bed-plate or table of my improved apparatus rigidly mounted on a supporting frame comprised of vertical and horizontal members 2 and 3, respectively, or in any other convenient and suitable manner.

The printing machine A is fixedly mounted at the forward end of said table while the carriage B of the paper feeding and cutting apparatus is slidably adjustable longitudinally of the table. Said carriage comprises rigidly connected side-plates 5, 5' slidably mounted upon the table and having upon their inner sides adjacent their lower edges rack-toothed bars 6. A transverse shaft 7 is rotatably mounted in the frame immediately below the table upon which toothed pinions 8 are keyed to engage the teeth of the respective racks and thus actuate the carriage through the manipulation of a hand-wheel 10 upon the outer side of the frame.

Guide-bars 11 are rigidly mounted upon brack-

ets 12 secured to the table along which the side-plates of the carriage are in sliding engagement. A longitudinal slot 13 is formed in each said bar and a pair of clamping-screws 15 are provided in each said side-plate engageable through the slots 13 with the respective guide-bar to secure the carriage at the desired working position.

The paper utilized in this apparatus is supplied in a roll, such as 16, mounted on an axially disposed arbor 17 to rotate freely or with slight resistance in the sockets 18 of a bracket 20 secured to the frame. The strip of paper, indicated by broken lines 21 in Fig. 1, may thence pass about a suitable tensioning device, as shown at 22, and thence is directed upwardly and rearwardly to engage about the peripheral surface of a main feed-cylinder 23 mounted for rotation at the rear of the carriage.

Said main feed-cylinder is keyed upon a rotary-driven shaft 25 projecting at both ends from the side-plates 5, 5' in which it is mounted. A secondary feed-roller 26 of considerably smaller diameter than the cylinder 23 is rotatably mounted in parallel axial alignment thereover in bearing-blocks 27, the mandrel 28 of the roller projecting at one side upon which is keyed a gear 30 in mesh with a larger gear-wheel 31 upon the cylinder-shaft 25 of relative pitch-diameters in said gears so that the cylinder and the roller will rotate at the same peripheral speeds.

Reliance is had mainly on the frictional contact of the paper strip upon the surface of the cylinder 23 for drawing the strip off of the roll 16 and advancing it at constant speed past the cutting appliances. To increase such area of contact 35 an idler-roller 32 is provided in close proximity to the lower periphery of the cylinder between which the paper strip is guided.

The bearing-blocks 27 are slidable vertically in guideways 33 in the side-plates and are urged upwardly tending to separate the roller 26 from the feed-cylinder by springs, not shown, positioned between the bottom of the respective bearing-block and the bottom of said guideways. A set-screw 35 is provided in the respective block-keepers 36 to depress the blocks and roller against the action of said springs to effect the amount of separation between the cylinder and roller desired. The roller 26 is desirably adjusted in spaced relation to the cylinder 23 approximating the thickness 60 of the paper passing therebetween, thus serving as a guide to direct the paper steadily and horizontally toward the cutting devices and maintaining it unswervingly in alignment and in a direct path.

37 indicates the main driving shaft on which the rotary paper-cutting appliances are mounted and it is rotated at a constant speed through a power-driven sprocket-chain 38 in operative engagement 5 with a sprocket-wheel 39 keyed to said shaft through power-transmitting connections to be hereinafter described.

Upon the opposite side of the carriage a gear-wheel 40 is keyed to the shaft 37 and which is in 10 mesh with a toothed pinion 41 rotatably mounted on a stud 42. Interchangeable gears, such as 43, of various pitch diameters to correspond, respectively, to the variations in speed-ratios desired between the feed-cylinder 23 and the drive-cutter 15 shaft 37 to effect the feeding of the several lengths of paper, are mounted on said stud and are compounded with the pinion 41 to be rotated therewith. The stud may be provided with a spring-pressed sleeve 45 to confine the gears 43 in engaged position through an intermediate split-washer 46.

A swinging yoke 47 is pivotally mounted at one 20 end upon the shaft 25, extending forwardly, and is formed with an arctuate slot 48 adjacent its forward end through which extends a hand-nut 49 to secure the yoke at adjusted positions. An intermediate gear 50 rotating on a stud 51 extending from the yoke is in constant mesh with a gear 52 keyed on the shaft 25. The adjustability of the 25 yoke admits of the meshed engagement of the gear 50 with any of the change gears 43 and thus effects the driving of the cylinder 23 at varying rates of speed, depending upon the change gear 43 utilized, and in opposite rotary directions to 30 that of the driving-shaft 37.

In Fig. 4 I have illustrated a preferred method of ensuring the proper meshing of the intermediate gear 50 with the various change gears 43, consisting of a block 53 rotatably adjustable upon 35 a stud 55 operable through a knob 56. Said block is formed with a plurality of flat faces 57 arranged at different elevations with respect to the pivotal center of the block and which are respectively adapted to support the projecting end 58 of the yoke at the various radial positions thereof when the corresponding gears 43 are in operation. Said 40 supporting faces are to be plainly marked to indicate with which gears they are correlated and hence safeguards the machine through the proper 45 meshing of the gears when changes of gears are made by inexperienced operators. In said view the bottom of the slot 48 in contact with the hand-nut 49 serves as a stop for the accommodation of the gear 43 of smallest diameter and the top of 50 said slot serves as a stop for the gear of largest 55 diameter.

A supporting bar 59 for the stationary knife 60 is rigidly secured between the side-plates 5, 5' and 60 includes a plane bearing-face 61 inclined upwardly and forwardly at approximately forty-five degrees from the horizontal. The knife is formed with a plurality of slots through which retaining-screws 62 secure it against said bearing-face and a plurality of setting-screws 63 are provided in screw-threaded bores in the bar 59 to engage the rear edge of the knife to effect such adjustments 65 thereof as needed.

A knife-head 65 upon which the rotated knife 66 is mounted is rotatably borne upon the drive-shaft 37 and is cylindrical in general form having two oppositely disposed longitudinal ribs 67 and 68 extending therefrom, of which the rib 67 carries the cutting-knife 66 upon its substantially radially directed face and the rib 68 serves as a counter-balance therefor.

The knife 66 is secured through slotted holes to the bearing-rib 67 by screws 70 admitting of proper adjustment of the knife. At about its midlength the knife-head is formed with a circumferential slot 71 extending thereabout for approximately 5 sixty degrees. A stop-pin 72 is fixedly secured in the shaft 37 and extends radially through the slot to limit the rotation of the knife-head on the shaft, as will be more fully explained.

At opposite ends of the knife-head 65 enlarged 10 cylindrical barrels 73, 73' are formed, the barrel 73 being formed with a tubular chamber 75 from its outer side. Within said chamber a coil-spring 76 is mounted under some tension, its inner end being secured to a button 77 projecting from the 15 shaft 37 while its opposite end is secured to a projection 78 extending into the chamber from the inner periphery of the barrel-chamber 75. Said spring tends to resiliently urge the knife-head forwardly upon the shaft 37 within limits determined by the slot 71.

80 indicates a brake-bar pivotally mounted at one end upon a transverse rod 81 forming one of the cross-members of the carriage. Said bar is formed intermediate its length to the approximate curvature on its under side of the periphery of the barrel 73 and is provided with a brake-shoe 82 to contact therewith. A vertically disposed spiral spring 83 is secured at its lower end to a pin 85 extending from the side plate 5 and at its upper 30 end is engaged with a forwardly projecting extension 86 of the brake-bar to provide the required amount of friction upon the brake-shoe. A stop-screw 87 extends through the extension 86 and engages a stop 88 projecting from the side plate 5 35 to afford limitation to the frictional effect of the spring 83 and to absorb a portion of the shocks developed.

A cam-wheel 90 is adjustably mounted on the gear 40 upon which cam a roller 91 is in engagement. Said roller is mounted upon a stud 92 extending laterally from the brake-bar 80 to engage and disengage the brake-shoe from the barrel 73 in response to the contours of said cam in conjunction with the spring 83.

The cam 90 is formed with its periphery for a major portion of its circumference set below a circular line which will engage said roller, hence the engagement of the brake-shoe 82 with the barrel 73 continues throughout this portion of 50 the rotation of the shaft 37. Such resistance upon the knife-head will cause the retardation of the knife-head until the stop-pin 72 engages the forward extremity of the slot 71 whereupon the knife-head will travel at the same rotary 55 speed as the shaft 37, the spring 76 being wound thereby to give an added tension.

At a predetermined point in the rotary travel of the knife-head, at approximately the point where the contact of the two knives is made to sever the 60 sheet, an elevation 93 is formed in the contour of the cam 90 preceded by an inclined portion 94, which elevation is slightly above a circular line which will engage the roller 91 and cause the lifting and release of the brake-mechanism 65 from its engagement with the barrel 73 whereupon the spring 76 will assert itself to impel the knife-head at a faster speed than the constant rotary speed of the shaft 37 and until the pin 72 engages the rear extremity of the slot 71, at 70 or about which point the elevation 93 is reduced, to below the circular line whereat it is in contact with the roller and thus cause the brake to move into engagement with the barrel 73 and again wind the spring 76 through the retarding of the 75

knife-head preparatory to making another cut in the paper sheet at its next revolution.

It will be seen that the cutting-edge of the stationary knife 60 is located in the horizontal plane of the paper-strip 21 moving forwardly upon the supporting plate 96 and which is somewhat in rearward of a vertical line drawn through the axis of the shaft 37 so that the knife 66 will contact therewith near the termination of its downward travel. But in such advantageous arrangement the knife 66 passes downwardly beyond the line taken by the advancing paper-strip after a sheet has been severed, hence should the knife travel at the speed governed solely by the shaft the paper-strip would strike thereagainst and be caused to buckle and defeat the purposes intended. As the rotation of the shaft 37 is maintained at a constant speed and the knife performs its cutting operation at each revolution thereof while the feed-cylinder 23 travels at a surface speed considerably in excess of that of the knife-head the advantage and importance of speeding up the rotary knife immediately or a short interval before making the severing cut and for a portion of its travel thereafter will be clearly evident.

The driving mechanism for actuating the paper-feeding and cutting apparatus and associated printing machine in synchronism will be readily understood. An electric motor 97, see Fig. 1, is mounted in the frame and is connected by a belt 98 to drive a pulley 100 keyed to a shaft 101. From a relatively small pulley 102 on the shaft 101 power is taken by a belt 103 and transmitted to a larger pulley 105 keyed on a shaft 106. A shaft 107 mounted in parallel with the shaft 106 is driven by a gear 108 from a gear 110 of the same dimensions on the shaft 106.

Sprocket wheels 111 and 112 on the shafts 106 and 107, respectively, are thus driven in opposite directions and are operatively connected by sprocket-chain 38 to the sprocket-wheel 39 of the shaft 37 and by the sprocket-chain 113 to the sprocket-wheel 115 of the printing-machine controlling the rotation of the printing-cylinder 116 and the various ancillary movements and functional parts of the machine.

In the operation of the machine and upon the determination as to the length of the sheets of paper to be cut the carriage is first adjusted upon the table with relation to its distance from the stop and gripping devices of the printing machine and particularly from the disappearing paper-stop 117 thereof. For convenience in setting the cutting machine the table 1 is provided with a series of calibrated lines and indices 118 therefor indicating the various standard or other lengths of paper which the apparatus is adapted to cut while a corresponding line 120 upon the side-plate 5 denotes the datum line from which the measurements are calculated and which is set in register with the proper line 118.

The carriage is moved by means of the hand-wheel 10 and is secured in rigid condition by the screw-clamps 15. The proper change gear 43 is then mounted on the stud 42 to rotate with the pinion 41 whereupon the yoke 47 is adjusted upon the respective face of the block 53 to bring the gear 50 into meshed engagement with the gear 43 and thus through the meshing of the gears 50 and 52 upon the shaft 25 to drive the feed-cylinder 23 in an opposite rotary direction to that of the knife-head.

Also it will be appreciated that the several change gears 43 each drive the feed-cylinder at

a different surface speed corresponding to the various lengths of paper to be cut and indicated by the lines 118, the cylinder advancing the paper a given length varying with the size of gear 43 employed while the shaft 37 whose speed remains unchanged makes a single revolution. 5

The strip of paper 21 is threaded upwardly from the roll 16 as described and about the feed-cylinder forwardly over the plate 96 and past the knife 60. The motor then being energized 10 to actuate both the cutting and printing apparatus the paper will be fed forwardly by the cylinder 23 at a uniform speed in excess of the rotary speed of the knife-head, excepting momentarily when the knife-head is free to rotate 15 at a higher speed under the action of the spring 76.

Thus upon a predetermined length of paper passing beyond the stationary knife 60 which length is governed by the selected gear 43 the 20 rotary knife 66 will have made a complete revolution since cutting the preceding sheet and will sever by a straight chopping cut or slightly shearing action with respect to the stationary knife the new sheet while the paper strip 25 continues its progress uninterruptedly.

The forward edge of the severed sheet will engage against the disappearing stop 117 of the printing machine, being impelled slightly forwardly and downwardly upon the apron 122 by 30 the forward and downward travel of the rotary knife, sufficient allowance of distance between the knife and said stops being afforded to cause the paper sheet to abut squarely upon the stops 117. In the continued progress of the cycle of 35 operations of the printing machine said severed sheet will then be gripped by the gripping-segments 123 acting in conjunction with the rollers 125 and advanced to the printing position beneath the printing cylinder 116 upon the momentary disappearance of the stops 117. The sheets will thus be severed and fed to the printing machine as they are cut, and at full speed, the printed sheets being delivered upon an extension 126 of the supporting frame. 45

The forward movement of the paper-strip 21 continues uniformly hence the desirability of speeding up the rotation of the knife-head about the portion of its travel when the paper is cut to avoid interference of the knife 66 with the 50 progress of the paper-strip and to effect the final stage of feeding the severed sheets to the printing mechanism. The exact point in the rotary travel of the knife 66 when the knife-head is released may obviously be adjusted by 55 the proper positioning of the cam 90.

In order to maintain the surface of the feed-cylinder 23 free of fibers and other foreign matter that may be deposited thereon from the paper moving thereover a U-shaped wiper-bar 127 is 60 provided in which a strip 128 of felt, or other suitable material, is retained in contact with the periphery of the cylinder. Said bar is supported by arms 129 rigid with a tubular body 130 rotatively mounted upon a transverse circular rod 65 131 rigid in the carriage. Said arms and body may be spring-pressed to cause the wiper-strip to bear resiliently against the cylinder. An arm 132 extends from the body 130 having a roller 133 at its extremity adapted to engage a cam-ring 134 under the spring pressure upon said body. Said cam-ring is rotatable with the cylinder 23 and is formed with a gap 135 therein. Said wiper may thus be in wiping contact with the cylinder for the greater part of its revolution 75

but at the point in its rotation corresponding to the juxtaposition of the gap and roller of the ring 134 and arm 132, respectively, the wiper is sharply separated from the cylinder with the effect of shaking off such dust and foreign matter as may have been wiped off.

Having described my invention, what I claim, is:—

1. Paper feeding and cutting apparatus for printing machines, comprising a stationary cutting-knife, a rotating drive-shaft driven at a constant speed, a knife-head mounted upon said shaft to rotate therewith having a cutting-knife fixedly mounted therein cooperative with said stationary knife, a feed-cylinder rotatively actuated from said shaft, the rotative speed of said knife-head being less than the surface speed of said feed-cylinder for the major portion of its travel.

2. Paper feeding and cutting apparatus for printing machines, comprising a stationary cutting-knife, a rotating drive-shaft driven at a constant speed, a knife-head mounted upon said shaft to rotate therewith having a cutting-knife fixedly mounted therein cooperative with said stationary knife, a feed-cylinder rotatively actuated from said shaft, the rotative speed of said knife-head being less than the surface speed of said feed-cylinder for the major portion of its travel, and with speed in excess to the surface speed of the feed-cylinder for the remaining portion of its travel.

3. Paper feeding and cutting apparatus for printing machines, comprising a stationary cutting-knife, a continuously rotating drive-shaft, a cutting-knife cooperative with said stationary knife mounted on said shaft to rotate within fixed limits thereon, a feed-cylinder rotatively actuated from said shaft, the rotative speed of said rotating knife being less than the surface speed of said feed-cylinder for the major portion of its travel, and with speed in excess to the surface speed of the feed-cylinder for the remaining portion of its travel immediately following its paper-severing contact with said stationary knife.

4. Paper feeding and cutting apparatus for printing machines, consisting of a carriage, a feed-cylinder rotatively mounted in the carriage and arranged to draw a strip of paper from a roll and advance it continuously, a drive-shaft rotatably journaled in the carriage and actuated at a constant speed, means to drive said feed-cylinder from said drive-shaft at selected speeds, and cutting appliances interposed in the travel of said paper strip, said cutting appliances including a knife-head and cutting-knife rotatably mounted upon the drive-shaft the rotative speed of which is less than the surface speed of said feed-cylinder for a portion of each revolution, and in excess thereof for the remaining portion of each revolution.

5. In paper feeding and cutting apparatus, a drive-shaft, means for rotatively actuating said drive-shaft at a constant speed, a knife-head mounted on said drive-shaft and rotatable within fixed limits thereon, spring-actuated means to urge said knife-head in the same rotatory direction as the drive-shaft, means to retard the motion of said knife-head upon said drive-shaft to increase the spring-tension thereon, and means to release said knife-head at a predetermined point in each revolution of the drive-shaft to give accelerated motion to said knife-head.

6. In paper feeding and cutting apparatus, a

drive-shaft, means for rotatively actuating said drive-shaft at a constant speed, a knife-head rotatively mounted on said drive-shaft, means to limit the rotative movement of said knife-head relative to said drive-shaft, spring-actuated means to urge said knife-head forwardly in the rotary direction of the drive-shaft, braking-means operable upon said knife-head to retard the motion of said knife-head upon the drive-shaft and thereby increase the spring-tension therebetween, and means operable in each revolution of the drive-shaft to release said braking-means to admit of said spring-means asserting itself to drive said knife-head at a speed in excess of that of the drive-shaft.

7. In paper feeding and cutting apparatus, a drive-shaft, means for rotating said drive-shaft at a constant speed, a knife-head mounted on said drive-shaft to rotate therewith and for a limited extent capable of rotation relative to the drive-shaft, a spring connected at its opposite ends to said drive-shaft and to knife-head and tending to urge the knife-head forwardly in the same rotary direction as the drive-shaft, a brake engageable with said knife-head to retard the motion of said knife-head upon the drive-shaft and to increase the tension of said spring, and means to effect the application and release of said brake in each revolution of the knife-head to respectively retard and accelerate the motion of said knife-head with respect to said drive-shaft.

8. In paper feeding and cutting apparatus, a drive-shaft, means for rotating said drive-shaft at a constant speed, a knife-head mounted on said drive-shaft, means to drive said knife-head from the drive-shaft admitting of limited independent motion of the knife-head in the rotary direction of the drive-shaft, a spring connected at its opposite ends to said drive-shaft and to the knife-head and tending to urge the knife-head in the same rotary direction as the drive-shaft, a brake engageable with said knife-head to retard the motion of the knife-head upon the drive-shaft and to increase the tension of said spring, and means to effect the application and release of said brake in each revolution of the knife-head to respectively retard and accelerate the motion of the knife-head with respect to the drive-shaft, said means consisting of a cam rotatable with the drive-shaft, and a roller contacting therewith operatively connected to said brake.

9. In paper feeding and cutting apparatus, a drive-shaft, means for rotating said drive-shaft at a constant speed, a knife-head rotatably mounted on the drive-shaft having a slot therein to receive a pin extending from the drive-shaft, said slot and pin admitting of limited rotary movement of the knife-head relatively to the drive-shaft, a spring connected at its opposite ends to said drive-shaft and to the knife-head and tending to urge the knife-head in the same rotary direction as the drive-shaft, a brake engageable with said knife-head to retard the motion of the knife-head upon the drive-shaft and to increase the tension of said spring, and means to effect the application and release of said brake in each revolution of the knife-head to respectively retard and accelerate the motion of the knife-head with respect to the drive-shaft, said means consisting of a cam rotatable with the drive-shaft, and a roller contacting therewith connected to said brake.

10. Paper feeding and cutting apparatus for

printing machines, comprising a fixed knife, a continuously rotating drive-shaft, a knife-head rotatively mounted on said drive-shaft to revolve relatively thereon within fixed limits, a knife rigidly mounted on said knife-head in cutting relation to said fixed knife, spring-actuated means to urge said knife-head in the rotary direction of the drive-shaft, means to retard the motion of the knife-head upon said drive-shaft and to thereby increase the spring tension thereon, a feed-cylinder arranged to draw a strip of paper from a roll and advance it between said knives to be severed thereby, means to actuate said feed-cylinder from said drive-shaft, and means to release said retarding means to accelerate the travel of the knife-head upon the drive-shaft at a selected point in each revolution thereof.

11. Paper feeding and cutting apparatus for printing machines, consisting in combination with a printing machine fixedly mounted upon a table and provided with stop and gripping devices to receive and advance the severed sheets of paper for printing, of paper feeding and cutting apparatus comprising a carriage adjustably mounted on the table, a feed-cylinder rotatively mounted in the carriage for drawing a strip of paper from a roll and advancing it towards the printing machine, a drive-shaft arranged to be rotated at a constant speed, a knife-head revolute on said drive-shaft and independently rotatable thereon for a limited extent, a knife rigidly connected to said knife-head, a knife fixed in said carriage in cutting relation with said first named knife, and means to drive said feed-cylinder from said drive-shaft, and at a higher rate of surface speed than the rotary travel of said first named knife as driven by said drive-shaft.

12. In paper feeding and cutting apparatus, variable speed power transmission devices including a train of gears, one gear of said train being selective to various diameters to obtain the desired speed variation, a gear of said train meshing with said selective gear being rotatively mounted upon a swinging yoke, said yoke being pivoted at one end and arranged to be adjustably secured at its opposite end, and a rotatively mounted block formed with a plurality of faces arranged at various distances with respect to the axis of the block and corresponding, respectively, with the diameters of said selective gears, said faces being arranged to support and gauge the outer end of said yoke to effect the desired meshing of said gear carried thereon with said selective gears, respectively.

13. Paper feeding and cutting apparatus, including a driven shaft, a knife-head mounted to rotate therewith and capable of relative rotary motion thereon within fixed limits, and a spring connected at its opposite ends to said shaft and to said knifehead.

14. In paper feeding and cutting apparatus, a rotatable shaft, a knife-head rotatively mounted on said shaft, and means to retard and accelerate the motion of said knife-head relative to the speed of said shaft in each revolution.

15. In paper feeding and cutting apparatus, a rotatable shaft, a knife-head rotatively mounted upon said shaft, and means to retard and accelerate the motion of said knife-head relative to the speed of said shaft in each revolution.

16. In paper feeding and cutting apparatus, a rotatable shaft, means for rotatably actuating

said shaft at a constant speed, a knife-head rotatively mounted for independent movement within predetermined limits upon said shaft, and means to retard and accelerate the motion of said knife-head relative to the speed of said shaft in each revolution. 5

17. In paper feeding and cutting apparatus, a rotatable shaft, means for actuating said shaft at desired speed, a knife-head rotatively mounted for independent movement within predetermined 10 limits upon said shaft, and means to retard and accelerate the motion of said knife-head relative to the speed of said shaft in each revolution.

18. In paper feeding and cutting apparatus, a rotatable shaft, means for actuating said shaft 15 at constant speeds, a knife-head rotatively mounted on said shaft, stops to limit the rotation of said knife-head upon the shaft, and means to successively retard and accelerate the motion of the knife-head relative to the speed of the 20 shaft in each revolution within the limits determined by said stops.

19. In paper feeding and cutting apparatus, a rotatable shaft driven at constant speeds, a knife-head mounted on said shaft for relative 25 rotation within predetermined limits, and means for intermittently driving the knife-head at speeds in excess to the speed of said shaft, said means consisting in a spring connected at its opposite ends to said shaft and to said knife- 30 head, a spring-pressed brake engageable with said knife-head, and devices for disengaging said brake.

20. In paper feeding and cutting apparatus, a rotatable shaft, means to drive said shaft at 35 constant speeds, a rotatably mounted knife-head on said shaft adapted for limited independent rotary motion thereon, and a spring connected at its opposite ends to said shaft and to said knife-head. 40

21. Paper feeding and cutting apparatus, including a rotatable shaft, means for driving said shaft at constant speed, a knife-head mounted for limited rotary motion on said shaft, a spring arranged to rotatably actuate said knife-head 45 upon said shaft, and means to alternately apply additional tension to said spring and to release the knife-head under such tension in each revolution of the shaft to cause said knife-head to rotate intermittently at a speed in excess to the 50 speed of the shaft.

22. Paper feeding and cutting apparatus, including a driven rotatable shaft, a knife head mounted upon said shaft to rotate therewith and capable of relative rotary motion thereon within 55 fixed limits, tension means interconnecting said shaft and said knife-head, and means to alternately increase and release the tension of said tension means in each revolution of the shaft 60 to respectively retard and accelerate the motion of said knife-head relative to said shaft.

23. Paper feeding and cutting apparatus, including a driven shaft, a stationary knife disposed in parallel with said shaft, a knife-head mounted on said shaft to rotate therewith and relatively thereof within predetermined limits, and a knife mounted on said knife-head in cutting relation with said stationary knife. 65

24. In paper feeding and cutting apparatus, a stationary knife, a rotatable shaft driven at a constant speed, a knife-head mounted upon said shaft having a cutting-knife secured thereon cooperative with said stationary knife, and means to accelerate the rotative speed of said knife- 70 75

head during each revolution relative to the speed of the shaft.

25. In paper feeding and cutting apparatus, a stationary knife, a rotatable shaft driven at a constant speed, a knife-head mounted upon said shaft having a cutting-knife secured thereon cooperative with said stationary knife, and means to accelerate the rotative speed of said knife-head at a predetermined point in each revolution relative to the speed of the shaft.

26. Paper feeding and cutting apparatus, including a driven shaft, a stationary knife disposed in parallel with said shaft, a knife-head mounted on said shaft to rotate therewith and relatively thereof within fixed limits, a knife se-

cured on said knife-head in cutting relation with said stationary knife, and means to accelerate the rotative speed of said knife-head in each revolution relative to the speed of the shaft.

27. In paper feeding and cutting apparatus, a stationary knife, a rotatable shaft driven at a constant speed, a knife-head mounted upon said shaft, a cutting-knife secured on said knife-head cooperative with said stationary knife, means to feed a strip of paper at a constant speed to be severed by said knives, and means to accelerate the rotative speed of said knife-head during each revolution relative to the speed of the shaft prior to the paper-severing contact of said knives.

ABE H. MARKOWITZ. 15
